UNITED STATES PATENT OFFICE

HARRY R. McDONALD, OF DUNKIRK, INDIANA, ASSIGNOR TO HART GLASS MANUFACTURING COMPANY, OF DUNKIRK, INDIANA, A CORPORATION OF INDIANA

DESIGN FOR A GLASS JAR

Application filed January 16, 1932. Serial No. 42,510. Term of patent 7 years.

To all whom it may concern:

Be it known that I, HARRY R. McDONALD, a citizen of the United States, residing at Dunkirk, in the county of Jay and State of Indiana, have invented a new, original, and ornamental Design for a Glass Jar, of which the following is a specification, reference being had to the accompanying drawings, forming part thereof.

Fig. 1 is a front elevation of a jar showing my new design;

Fig. 2 is a side elevation of the jar illustrated in Fig. 1;

Fig. 3 is a plan of the jar illustrated in Fig. 1.

I claim:

The ornamental design for a glass jar, as shown.

In witness whereof I have hereunto set my hand at Dunkirk, Indiana, this 11th day of January, A. D. one thousand nine hundred and thirty-two.

HARRY R. McDONALD.
